his Atty's

UNITED STATES PATENT OFFICE.

FRANK THOMPSON, OF CHICAGO, ILLINOIS, ASSIGNOR TO HIMSELF, THOMAS A. FRASER, AND OTTO W. MEYSENBURG, OF SAME PLACE.

DESIGN FOR A TRUCK-BOLSTER.

SPECIFICATION forming part of Design No. 27,099, dated May 25, 1897.

Application filed April 14, 1897. Serial No. 632,182. Term of patent 14 years.

To all whom it may concern:

Be it known that I, FRANK THOMPSON, a citizen of the United States, residing at Chicago, in the county of Cook and State of Illinois, have invented and produced a new and original Design for Truck-Bolsters for Railway-Cars, of which the following is a specification, reference being had to the accompanying drawings, forming part thereof.

10 Figure 1 is a side view of my newly-designed truck-bolster for railway-cars. Fig. 2 is a plan view of the same. Fig. 3 is a sectional view taken on the line $x x$ of Fig. 1.

15 As shown in the drawings, the leading or material feature of my design consists in forming the upper and lower plates A and B of the truck-bolster so that they approach each other at their ends and at their centers are substantially equidistant from a straight line 20 drawn from the points of contact of the ends of the two plates, or, in other words, these

two plates form when viewed from the side, as in Fig. 1, an approximation to an elongated diamond-shaped figure. The plates A and B are flattened at their centers, as indicated, respectively, by a and b . A web C of an approximately elongated diamond shape is interposed between the two plates A and B, which webs, as shown clearly in Fig. 3, are set back a short distance from the edges of 25 30 said plates.

Having described my invention, what I claim as new, and desire to secure by Letters Patent, is—

The design for a truck-bolster for railway-cars, substantially as herein shown and described.

FRANK THOMPSON.
